UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

BAG FORMING AND FILLING APPARATUS.

Application filed February 16, 1925, Serial No. 2,489. Renewed October 21, 1925.

My invention relates to bag forming and filling apparatus, and more particularly to certain features of apparatus for forming bags from an elongated tube of bag-making material and for filling such bags as formed. In order that these features may be fully understood, a complete description will be given of the apparatus in which they are included.

10 In the accompanying drawings forming a part of this specification, Figure 1 is a side elevation of apparatus embodying the features of my invention, with parts broken away; Fig. 2 is a front elevation of the apparatus shown in Fig. 1; Fig. 3 is a view similar to Fig. 2 showing some of the parts in another position; Fig. 4 is an enlarged section on the line 4-4 of Fig. 2; Fig. 5 is an enlarged view, partly in section, of a 20 portion of the apparatus; Fig. 6 is a front view of the part shown in Fig. 5; Figs. 7 and 8 are views, similar to Figs. 5 and 6, of a slightly modified form.

25 My apparatus includes a framework 10 from which rise vertical guides 11 for a sewing head 12 and guides 13 for a weighing device 14. A coil of tubing 15 is mounted on journals 16 in bearings 17, suitably located with relation to frame 10. 30 Tube 18 from coil 15 is fed upward over pulley 19, and thence downward to the weighing and sewing mechanisms. Pulley 19 is supported by a rope or cable 20, which passes over a fixed support 21 and is adjustably secured in any desired manner, as 35 by winding about a button 22.

40 Within the portion of the tube which extends between pulley 19 and the sewing machine there is a float member 23 supported by a hook 24, which is adapted to be positioned over pulley 19 and inside of the tube, so that the float remains at a substantially 45 fixed distance from pulley 19 while the tube is drawn past the pulley and float. The float comprises a tubular body portion having, at its upper end, a flapper member 25, which is normally in the position shown in Fig. 5. The weighing apparatus is provided with a downwardly directed discharge tube 26 having on its forward edge a knife 27.

45 In the operation of the apparatus, tube 18 is threaded over hook 24 and float 23 until its lower end is on a level with the 50 sewing machine, when the lower end is

closed by sewing a seam across it. Thereafter the end is drawn down until it is substantially even with platform 28. Thereupon the tube and float are pressed against feed pipe 26 so that knife 27 forms a transverse slit in the side of the tube and enters beneath flapper 25. Flapper 25 has a flange member 29 in position to contact the front side of the float and limit the movement of the flapper and prevent contact of the knife 65 with the walls of the float.

60 The relative proportions of the parts are such that, when the flange or toe member 29 contacts the front wall of the float, feed tube 26 registers with the opening between 70 the edges of the slit formed by knife 27 and with the opening through the tubular portion of float 23. While the parts are in that position, a properly weighed or measured charge of material is discharged 75 through feed pipe 26 and float 23 into the lower end of the tube.

70 After the charge has been deposited in the lower end of the tube, it is swung to the position in which it is shown in Fig. 3 80 and lowered upon belt 31, by which it is fed along to the sewing machine. When the tube is swung away from feed pipe 26, the upper edge of the slit is forced outward by flapper 25, so that it will not catch on the 85 rear edge of float 23. Ears 30 are provided at the sides of the flapper 25 in position to spread the tube so that the upper edge of the slit will not catch on the sides of the float when the tube is drawn down onto 90 belt 31.

95 The type of apparatus disclosed in the drawings is adapted for use with paper tubes, and the sewing head is provided with means for guiding a reinforcing tape 32 into position so that the closing seams are sewed through the tape. The sewing head may be provided with a cutter (not shown) which will sever the tube and reinforcing tape between the lines of stitching. 100

100 When the tube is swung to one side, as shown in Fig. 3, there is a tendency for the tube to wrinkle or fold at 33, immediately above the top 34 of the charge which has been positioned in the tube. This may be 105 taken advantage of in order to form a bellows-fold in the top of the tube at this point. As the tube is fed through the sewing machine, it is swung into a position substantially vertically beneath pulley 19 so 110

that the tube is straightened out, and a similar bellows-fold is formed in the other side of the tube.

After the tube has been closed and severed 5 in this manner so as to complete a filled package, the closed end of the remaining portion of the tube is drawn down until it is substantially even with platform 28. The operator may sometimes determine the 10 distance to which the tube is drawn down, more easily than by judging from its being even with platform 28, by placing the fingers upon the slit formed by knife 27, or upon a previously printed mark 35 on the 15 front of the tube, and drawing the tube down until the slit or mark registers with groove 36 in the float. The use of mark 35 is especially advantageous where labels 20 37 are printed upon the tube, because this enables the successive closures to be formed in proper relation to the labels on the bags.

The elevation of the sewing machine and the weighing and filling mechanism is adjusted so that the sewing machine will form 25 seams upon the opposite sides of the slit and so close the filled bag and the bottom end of the remaining portion of the tube, and the severing knife completes the severance 30 of the tube walls at the point where they have been slit by knife 27.

As will be seen, the float 23 is a little longer than one bag length so that, when the bottom of the tube rests upon platform 28, the slit through which the previously 35 formed bag was filled is opposite groove 36, and material is prevented by float 23 from leaking out through this previously formed slit. With some materials and for some purposes it might be possible to make 40 the float shorter and have only one bag length below the slit at the time of filling. The objection to this method of procedure as a general practice is that it renders difficult proper filling of the bag, because of 45 the room taken up by the float, and there is danger of the charge not all passing out of the feed pipe before the tube is withdrawn therefrom. Pulley 19 is adjusted so that the top of the tubular portion of 50 the float is the proper distance above platform 28.

If desired, filling openings may be formed in the tube before the filling operation instead of forming the openings at the same 55 time that the feed pipe is inserted, but the latter method prevents any difficulty in obtaining proper registration of the feed pipe with the opening.

Different forms of openings and feed 60 pipes may be used, but a straight transverse slit is advantageous as it may be formed at the point where the bags will be divided from the tube, and so requires no additional closure. Furthermore, such a slit is 65 best opened by spreading the middle por-

tions of the two edges apart on opposite sides of a straight line connecting the ends of the slits, so that an oval opening is formed. If the slit were opened in such a way as to cause excessive strain at the ends thereof, the material might tear along irregular lines which might pass beyond the lines of the prospective closures and might cause difficulty in the feeding of the tube over the float.

In the example shown, when a slit is formed by knife 27, the edge 38 below the slit is held in position by the float while the edge 39, above the slit, is pressed towards the other wall of the tube by feed pipe 26, so that, as shown in Fig. 4, the two edges of the slit are placed at substantially equal distances from a line connecting the ends 40 of the slit. Opening up the slit in the manner described not only provides a large opening in proportion to the size of the slit, but also enables the insertion of the charge in a line substantially parallel to the axis of the tube so that it passes readily through the tube and into position against its closed end.

In the form of float shown in Figs. 7 and 8, a different device is provided for determining the distance to which the bag is drawn down around the tube. In these figures the float is made the same as that shown in Figs. 5 and 6 except for groove 36, and corresponding reference numerals are applied, with the numerals primed in Figs. 7 and 8. Instead of providing a groove 36, a position-determining member may be provided comprising a longitudinal strip 41 having a hook 42 adapted to be hooked into a notch in the upper edge of float 23'. At the lower end of member 41 there are transversely extending arms 43. When the tube is drawn downward the upper edge of the slit may be pressed against the float so that it will catch on the upper sides of arms 43 and limit the downward movement of the tube. This form of limiting device is adapted for use where there are to be frequent changes in the length of bags formed, because the limiting member may be withdrawn at any time through the slit and replaced by one having a longer or shorter member 41.

In the form of float shown, the lower corners are flattened and extended outward at 44 so as to form two substantially parallel flat plates at the lower end of the float, which may be used where desired to open up squarely the bottom of the tube before the charge is delivered thereto.

Salt, beans, rice and similar materials require little settling or packing in bags, and fairly satisfactory results are obtained with little more manipulation of the filled tube-end than naturally accompanies its movement from platform 28 to belt 31. Where

the nature of the packaged material or other circumstances render more settling or packing desirable, a jigging table may be substituted for platform 28, feed pipe 26 may be so lengthened that the material will drop with self-packing force, or other settling or packing expedients may be employed without material change in the essential features of the invention.

10. While a complete method and apparatus have been described, in order that the invention may be fully understood, there is claimed herein only features which cannot be claimed in my copending application, 15 Serial No. 28,321, filed May 6, 1925, in which there is disclosed and claimed an apparatus involving many of the features disclosed in this application.

What I claim is:

16. 1. In packaging apparatus, a pulley adapted to have a bag tube passed thereover, a float adapted to be inserted within a bag tube and having a hook adapted to hook around the pulley between the walls of a tube and retain the float in place while a tube is moved forward past the pulley and float.

2. In apparatus for packaging material, means for supporting rotatably a coiled tube, a float, means to guide a tube from the coil support to and around the float,

means to maintain the float stationary while the tube is advanced therearound, and means to feed material through an opening in the side of the tube and through the float into, 35 the tube beyond the float.

3. In apparatus for packaging material, a float, a pulley over which a tube may pass to and around the float, a hook attached to the float and adapted to hook over the pulley 40 to maintain the float stationary while the tube is advanced therearound, and a feed pipe in position to feed material through an opening in the side of a tube which is positioned around the float and into a portion 45 of the tube held expanded by the float.

4. In apparatus for packaging material, a float having a tubular portion longer than the package to be formed, a bead element positioned transversely on the exterior of 50 said tubular portion, and a shank maintaining said bead element one bag-length distant from the upper end of the float, means to maintain the float stationary while a tube is moved forward therearound, and a feed 55 pipe in position to feed material through an opening in the side of a tube which is positioned around the float and into a portion of the tube held expanded by the float.

In testimony whereof, I have hereunto 60 signed my name to this specification,

ADELMER M. BATES.
